UNITED STATES PATENT OFFICE

EDWARD KIRBY BOTTLE, OF ELMIRA, NEW YORK, ASSIGNOR TO AMERICAN SALES BOOK COMPANY, LIMITED, OF TORONTO, ONTARIO, CANADA, A CORPORATION OF ONTARIO

RECORD STRIP EASEL AND DEFLECTOR FOR AUTOGRAPHIC REGISTERS

Application filed August 8, 1928. Serial No. 298,190.

This invention relates to improvements in manifolding machines such, for example as autographic registers and more particularly, with reference to some of its specific features, it relates to improvements in means for positioning the inscribed record strips or tickets as they emerge from the feeding mechanism.

It is the general object of the invention to provide, in machines of the class mentioned, an improved arrangement for disposing of the inscribed record strips as they emerge from the feeding mechanism.

A more particular object is to provide for machines of the class mentioned an improved record strip deflector whereby inscribed record strips, as they emerge from the feeding mechanism, are positioned for convenient observation by the operator, and for convenient manual removal.

Another object is to provide for machines of the class mentioned an improved record strip deflector which can expeditiously be placed in operative or inoperative position.

Another object is to provide for machines of the class mentioned an improved strip deflector adapted for application to autographic registers or like machines of existing construction, and which can be easily placed in operative position thereon or removed therefrom.

Another object is to provide for machines of the class mentioned an improved strip deflector and support which is mounted on the machine so that it can be moved into collapsed condition or extended into operative position.

A further object is to provide, for machines of the class mentioned, an improved easel providing in a simple and satisfactory manner, a temporary or detachable filing or storage compartment into which one or a plurality of the inscribed record strips may be folded for temporary disposal thereof.

Another object is to provide an improved easel for machines of the class mentioned, having a main and auxiliary filing compartments for one or a plurality of inscribed record strips, and providing for the storage,

in the separate compartments, of different parts of a continuous record strip.

Another object is to provide, for machines of the class mentioned, an improved easel forming an attachment for effecting conversion of machines of the non-filing type into machines of the filing type.

Other objects will be in part pointed out in the following detailed description of certain illustrative, but preferred embodiments of the invention and will be in part obvious in connection therewith.

The invention accordingly comprises the features of construction, combinations of elements, and arrangement of parts, which will be exemplified in the construction hereinafter set forth and the scope of the application of which will be indicated in the claims.

For a complete understanding of the nature and objects of the invention reference is had to the following detailed description of the preferred embodiments, and to the accompanying drawing, in which:

Fig. 1 is a central vertical longitudinal section through an autographic register equipped with one form of the invention, the illustration being partially diagrammatic;

Fig. 2 is a perspective view of the record strip deflector shown in Fig. 1;

Fig. 3 is a partially diagrammatic perspective view with parts in longitudinal vertical section of a different embodiment of the invention and including a temporary filing compartment applied to an autographic register of standard construction;

Fig. 4 is a side elevation of a different form of record strip deflector applied to an autographic register of standard construction;

Fig. 5 is a perspective view of the strip deflector shown in Fig. 4;

Fig. 6 is a fragmentary perspective view showing a modification of the strip deflector of Fig. 5;

Fig. 7 is a partially diagrammatic elevational view with parts in section, of an autographic register equipped with still another form of strip deflector, and

Fig. 8 is a perspective view of the strip deflector shown in Fig. 7.

Referring first to the embodiment of the invention as shown in Figs. 1 and 2, a manifolding machine of the type known as autographic registers is illustrated in order to disclose the application of the invention to this type of machine. The register has a casing 10 with an end wall 11 and a platen 10 or writing table 12 horizontally positioned for supporting continuous record strips A in writing position. These record strips may be of known form, each preferably having blank forms arranged in a series therealong and having a longitudinal series of marginal apertures along each longitudinal edge for cooperation with the strip feeding mechanism so as to feed and align the strips in a manner well-known in the art, and as 15 disclosed in the patent to Clarence L. Johnston #1,658,127 for autographic registers, dated February 7, 1928.

These record strips may be folded together in a zig-zag supply pad as in the Johnston 20 patent and filed in a supply compartment in the register casing.

The feed shaft 13 carries two spaced feed disks 14 of a construction similar to that disclosed in the Johnston patent cooperating 25 with a superposed feed roll 15 mounted for yielding upward movement in the housing 16 which may be pivoted to the casing by means of arms 17 so as to swing upwardly and forwardly from the position illustrated in 30 Fig. 1. The construction of the strip feeding mechanism and the arrangement thereof with reference to the platen and to the supply compartment of the machine may be similar 35 in general to that disclosed in the Johnston 40 patent mentioned, or they may be of other known form.

A cover plate 18 may be secured to the upper margin of the casing walls adjacent to the feed mechanism substantially at the level 45 of the platen 12 and at the upper edge of the end wall 11 a transverse slot 19 is provided for the reception of the strip deflector 20. As shown in Figs. 1 and 2, this strip deflector may be in the form of a plate of 50 metal or similar stiff material and is mounted so as to be extended in an upwardly inclined position at the forward end of the machine as shown in Fig. 1, or to be retracted in telescopic position within the casing. This 55 deflector in the embodiment shown, is supported by spaced rods or bars 21, 22 and 23, extending transversely of the casing and it is also supported upon the end wall 11 to the bottom of the slot 19.

60 The strip deflector is preferably bowed or curved longitudinally with its convex face upwardly as shown, and at its rear end it is provided with a stop or lug 24 positioned for contacting with the supporting rod 22 65 when the deflector is extended.

A downwardly extending flange 25 may be formed at the forward end of the deflector serving as a handle for extending or retracting the deflector and also as a stop contacting with the adjacent face of the end wall 11 to 70 limit retraction. The deflector may be guided against undue edgewise movement by means of lugs 26 carried by the rod 21 and also by the terminals of the slot 19.

As the strip deflector 20 is intended for the purpose of supporting the loose ends of the forwardly fed record strips A, it may be of any convenient width for this purpose, and it may be formed of wires instead of a plate as shown. Its width, however, is preferably less than the distance between the feed disks 14 so as to be received between the latter.

It will now be seen that when the deflector is extended as in Fig. 1, it functions to receive and support the record strips as they emerge from the feed mechanism deflecting them upwardly into a position in which they may be easily observed by the operator and readily grasped and removed as desired. 85 When not needed for use the deflector may be collapsed or telescoped into the casing, its longitudinal curved form preventing the rear end thereof from projecting downwardly too far into the storage compartment and at the same time, functioning to dispose the deflector in its upwardly inclined position when extended. Due to its simple construction and the simple construction of the supporting arrangement, the deflector may be 90 easily applied to machines of existing construction with very little modification of the latter.

The embodiment of the invention, shown 105 in Fig. 3, is intended more especially for autographic registers unprovided with a strip storage compartment, and the arrangement shown provides a temporary storage compartment for one or more of the record strips.

The register shown in Fig. 3 is similar to that of Fig. 1 above described and corresponding parts are designated by the same reference numerals. In order to form the temporary filing compartment forwardly of the end wall 11 of the register an easel 27 is provided having a base plate 28 and an angularly upwardly extending back plate 29 preferably inclined rearwardly and upwardly from its lower edge as shown. These two plates or walls may be formed of a single sheet of metal or the like, bent into the desired form or they may be formed of two or more sheets attached together. As shown in Fig. 3, it will be observed that the base plate 110 28 may extend underneath the register whereby the latter may rest upon said base plate so as to secure the easel in its correct position relatively to the end of the register, or if preferred the easel may be secured in position by some other convenient means. By virtue of 115 27

this arrangement, the easel is sufficiently secured to the register by the frictional engagement of the latter as it rests by its own weight upon the base plate 28.

- 5 In some of its aspects, the deflector plate 30 is similar to the deflector plate 20 above described and it serves a similar purpose in deflecting the record strips A upwardly and supporting them in convenient position for 10 observation or for removal. In this case, however, the deflector 30 is supported at its rear end slightly above the adjacent cover plate 18, leaving a narrow space between the rear edge of the deflector and the cover plate 15 for the reception of one or more record strips A issuing from the feeding mechanism.

In the embodiment shown, the rear edge of the deflector plate is carried by a support shown in the form of a light rod or wire 31 appropriately supported by the machine casing in any convenient manner (not shown). As shown, the edge of the deflector plate 30 may be bent or offset to provide a flange or bead engaging the supporting rod 31. The rear 25 edge of the deflector plate or the wire 31 thus acts as a diverter or separator for separating the file strip from the other strips which are moved upwardly upon the deflector 30.

The outer end of the deflector may be provided with a downwardly extending flange 32 passing over the upper edge of the back wall 29 of the easel, the outer end of the deflector and the easel thus being mutually supported. The base 28 of the easel may be appropriately 35 attached to the register or it may be retained in position by extending it beneath the forward end of the register as shown.

In some cases, it is desirable to provide the easel with a false or separate back 33 spaced 40 slightly from the back 29 and preferably arranged substantially parallel with the latter. The false back 33 is preferably joined with the base plate 28 intermediate the edges thereof as shown and preferably terminates at its 45 upper edge below the upper edge of the back plate 29.

The false back 33 provides a storage space or compartment 34 in which a desired number of the inscribed record sheets or tickets may 50 be manually stored, such as that represented by a day's business, an hour's business or some other period. In placing the inscribed sheets or tickets in the storage compartment 34, it is unnecessary to sever the strip which may 55 extend continuously over the upper edge of the false back 33 as shown.

When the record strips A are loaded into the machine, one or more of the lower strips will be threaded through the space between 60 the diverter 31 and the cover plate 18 while the remaining strips are threaded above the diverter so as to be extended up the inclined face of the deflector 30. Since as above mentioned, the record strips are preferably folded 65 into a zig-zag supply pad, they are creased

transversely at intervals and have a tendency to refold along these creased lines.

Therefore, as the lower or file strip is fed forwardly, it may cooperate with the surfaces of the easel against which it is projected by 70 operation of the feeding mechanism so as to cause the strip to be directed naturally into folded position within the temporary file compartment provided between the end wall 11 and the false back 33. It is a simple matter to manually adjust the folds of the file strip in this compartment in case the folding under action of the feeding mechanism is 75 not compact or complete.

In the modification of the invention shown in Figs. 4 and 5, an autographic register of the types above described is shown and corresponding parts are similarly numbered, but the form shown may be provided in its casing beyond the feed roll housing 16 with 80 a storage or filing compartment for one or more of the record strips as disclosed in the Johnston patent mentioned above. The top or cover plate at the end of the machine beyond the feeding mechanism has lateral extensions providing guiding supports or rails 35 preferably extending laterally at both sides of the machine slightly beyond the side walls thereof, or these rails may be otherwise formed. These supporting rails act as guideways 85 for adjustably supporting the upwardly inclined strip deflector plate 36.

At its lower end, the deflector 36 is provided with laterally opposed downwardly extending angularly disposed supporting extensions or lugs 37 flanged inwardly toward each other at their lower extremities as at 38. A channel 39 is thus provided at the lower end of the deflector for receiving the rails 35 and the lower end of the deflector above the 90 channels 39 may rest against the top plate of the register to provide a support.

It will therefore be seen that the strip deflector 36 may be supported in upwardly inclined position as shown, performing functions similar to those of the deflectors 20 and 30 above described. The deflector 36 may be readily slid or adjusted backwardly and forwardly along the supporting rails 35 and will be supported in operative position in any adjustment thereof by means of the supporting lugs described.

Fig. 6 shows a modification of the means shown in Fig. 5 for supporting the deflector plate in operative position. In this case the inwardly extending flanges 38' at the lower ends of the extensions 36 are turned upwardly and backwardly at their ends so as to form a backwardly extending contact plate 40 spaced upwardly slightly from the flange 38'. Since the flange 38' may be of springy material, the contact plates 40 provide a yielding means for engaging the lower edges of the guiding and supporting rails 35, thus tending 100 to hold the deflector in correct operative position.

sition at all times to permit easy adjustment forwardly or backwardly.

The form of the invention shown in Fig. 7 is applied to an autographic register embodying the features substantially as in Fig. 1 above described. In this case, the deflector 41 is provided at its lower edge with an angularly disposed attaching flange 42 adapted to be secured to the register as by placing it under the rear cover plate 18 and securing the latter in position as shown. The operation of this deflector is substantially the same as in the case of the deflectors 20 and 36 above described.

15 Since certain changes may be made in the above construction and different embodiments of the invention could be made without departing from the scope thereof, it is intended that all matter contained in the 20 above description or shown in the accompanying drawing shall be interpreted as illustrative and not in a limiting sense.

It is also to be understood that the following claims are intended to cover all of the 25 generic and specific features of the invention herein described, and all statements of the scope of the invention which, as a matter of language, might be said to fall therebetween.

Having described my invention, what I 30 claim as new and desire to secure by Letters Patent is:

1. In an autographic register, in combination, record strip feeding means, a detachable easel having a rear wall and a base plate 35 forming means for securing the easel in position relatively to the point of emergence of the strip from the feeding means, said easel providing a temporary compartment positioned below said point of emergence 40 into which one or more of the record strips may be folded.

2. In an autographic register, in combination, record strip feeding means, a detachable easel having a rear wall and a base plate forming means for securing the easel in position relatively to the point of emergence of the strip from the feeding means, said easel providing a temporary compartment positioned below said point of emergence 45 into which one or more of the transcribed record strips may be folded, a diverter for diverting one or more strips, from a plurality of superposed strips, into filed condition in said compartment, and a deflector positioned above said compartment 50 for temporarily supporting the undiverted record strips.

3. In an autographic register, in combination, record strip feeding means, a detachable easel having a wall cooperating with the wall of the register to provide a temporary compartment positioned below the point of strip emergence into which one or more of the transcribed record strips may be folded, 55 and a diverter for diverting one or more

strips, from a plurality of superposed strips, into filed condition in said compartment.

4. In an autographic register, in combination, record strip feeding means, a detachable easel having a rear wall and the base 70 plate forming means for securing the easel in position relatively to the point of emergence of the strip from the feeding means, said easel providing a temporary compartment positioned below said point of emergence 75 into which one or more of the transcribed record strips may be folded, a diverter for diverting one or more strips, from a plurality of superposed strips, into said compartment, and a deflector positioned above 80 said compartment for temporarily supporting the undiverted record strips, said deflector having a support at one end thereof adjacent said diverter and at its outer end having a support upon said rear wall.

5. In an autographic register, in combination, record strip feeding means, a detachable easel having a rear wall and a base plate forming means for securing the easel in position relatively to the point of emergence of the strip from the feeding means, said easel providing a temporary compartment positioned below said point of emergence 90 into which one or more of the transcribed record strips may be folded, and a supplemental wall spaced from said back wall so as to provide an auxiliary strip storage compartment.

6. An easel for autographic registers, including spaced upright substantially parallel walls providing therebetween an auxiliary strip storage compartment and a base plate 100 extending beyond both of said walls.

7. An easel for autographic registers, including spaced upright substantially parallel walls providing therebetween an auxiliary strip storage compartment, an adjacent storage compartment and a base plate extending beyond both of said walls, the inner 105 wall being substantially lower than the outer wall whereby a folded record strip may extend continuously between the compartments.

8. An easel for autographic registers including spaced upright walls providing therebetween an auxiliary strip storage compartment and a base plate extending beyond both of said walls, the forward face of one of said walls making an obtuse angle with said base plate.

9. An easel for autographic registers including spaced upright walls providing therebetween an auxiliary strip storage compartment and an adjacent storage compartment between one wall and the register, and a base plate extending beyond both of said walls at corresponding sides thereof, the inner wall being substantially lower than the outer wall whereby a folded record strip 125 may extend continuously between the com- 120

parts, both of said walls inclining away from the extending part of the base plate.

10. In an autographic register, in combination, a detachable record strip easel positioned outside of the register and having portions forming therewith a temporary compartment for the reception of a record strip, said easel having a base plate forming a position retaining device for the easel, and a wall extending upwardly from said base plate.

11. In an autographic register, in combination, a detachable record strip easel positioned outside of the register and having portions forming therewith a temporary compartment for the reception of a record strip, said easel having a base plate forming a position retaining device for the easel, and a rear wall spaced from the register and inclining upwardly away from the latter.

12. In an autographic register, in combination, a detachable record strip easel positioned outside of the register and having portions forming therewith a temporary compartment for the reception of a record strip, said easel having a base plate forming a position retaining device for the easel, and walls spaced from the register and attached to and rising above said base plate and spaced apart to provide an auxiliary strip storage compartment.

13. In an autographic register, in combination, a detachable record strip easel positioned outside of the register and having portions forming therewith a temporary compartment for the reception of a record strip, said easel having a base plate forming a position retaining device for the easel, and walls spaced from the register and attached to and rising above said base plate and spaced apart to provide an auxiliary strip storage compartment, both of said walls being inclined away from the register and upwardly from said base plate.

45. In testimony whereof I affix my signature.
EDWARD KIRBY BOTTLE.
